UNITED STATES PATENT OFFICE.

CHRISTOPHER COLUMBUS PARKER, OF KIDDVILLE, MISSOURI.

IMPROVEMENT IN LUBRICATING DEVICES FOR VEHICLE-AXLES.

Specification forming part of Letters Patent No. 145,231, dated December 2, 1873; application filed April 8, 1873.

To all whom it may concern:

Be it known that I, CHRISTOPHER C. PARKER, residing in Kiddville, in the county of Sullivan and State of Missouri, have invented certain new and useful Improvements in Lubricators for Wagon-Axes, of which the following is a specification:

This invention relates to certain new and useful improvements in lubricators for wagon-axes; and it consists of an oil-vessel, the discharge or supply end of which is made tapering or conically-shaped, and fitted with a valve or stopper supplied with a stem or rod passing up through an orifice in the cover, and provided with an adjustable head or nut having a bale or handle. The said cover, which is furnished also with a bale, is held down in place through the assistance of a spring-catch, while the end of the oil or lubricating vessel is constructed with a screw for fastening that end thereof into the metallic thimble which receives the axle.

In the annexed drawing, Figure 1 represents a view, in elevation, of my improved lubricator, and a transverse vertical section of the hub of a wheel, showing my device applied thereto. Fig. 2 is a vertical central section of the former, and Fig. 3 a plan view of the same.

In the several figures corresponding parts are designated by similar letters.

A refers to a cylindrical or other suitably-shaped vessel for holding the oil or other lubricating substance, to the lower end of which vessel is supplied a screw-threaded neck, a, which enters a threaded opening made in the thimble a¹ of the hub a² for the purpose of fastening that end in place, the oil or grease being supplied or fed to the axle A' through the said neck. Within the lower part of the vessel A is secured, in any known way, a funnel-shaped or tapering vessel, communicating with the neck a, and constituting a part of the vessel just named. To this funnel-shaped vessel is fitted a valve or stopper, B, which acts as a cut-off to the flowing oil, entering the axle-chamber when it is pushed downward, but when elevated or lifted out of the said funnel it allows the oil to flow to the axle. A stem or rod, b, attached to, and for the purpose of lifting and lowering, the said valve, extends

up through the cover C, and is supplied with an adjustable head or nut, c, having a bale, c¹. The object of this arrangement is to enable the valve B to be grasped, through the said bale c¹, and raised and lowered, or opened and shut, when desired, without removing the cover C, and, further, to permit of the latter being removed without disturbing the valve or cut-off B, as it will be plainly seen that, by unscrewing the adjustable head c, the said cover will be disconnected from the stem b of the valve, and thus leave the said stem unaffected by the removal of the cover. A diaphragm or disk, b', is attached to the stem b at such a point as that the said valve B will be prevented from being lifted out of its seat further than to allow the oil to flow out of the vessel at the desired rate or speed. The cover or cap C is supplied with vents c² c² and the bale c³ for lifting it from its place. The vessel A is inserted or set into the hub so as that its upper end shall rest below the surface of the latter, and then protected from the dust and mud by a lid or cover hinged over the opening having the said vessel. A spring-catch, D, fastened to the side of the vessel A, overhangs the cap or cover C, and assists in holding it down upon the vessel A. Lugs E E are fastened to the opposite sides of the vessel for the reception of suitable fastenings for attaching the upper end thereof to the hub.

Having thus fully described my invention, what I claim, and desire to secure by Letters Patent, is—

1. The combination, with the vessel A, having the conically-shaped valve-seat, of the valve or cut-off B, the stem of which is supplied with a diaphragm, b', and a handle, substantially as and for the purpose set forth.

2. The combination of the vessel A, cap or cover C c³, valve B b, having the adjustable head c and bale c¹, and the diaphragm b', substantially as and for the purpose specified.

In testimony whereof I have hereunto signed my name this 25th day of November, 1872, in presence of two subscribing witnesses.

CHRISTOPHER C. PARKER.
